UNITED STATES PATENT OFFICE.

LEON TROXLER, OF NEW ORLEANS, LOUISIANA.

PROPELLER-BLADES.

1,097,199.

Specification of Letters Patent. Patented May 19, 1914.

Application filed October 21, 1911. Serial No. 656,071.

To all whom it may concern:

Be it known that I, LEON TROXLER, a citizen of the United States, residing at the city of New Orleans, in the parish of Orleans and State of Louisiana, have invented certain new and useful Improvements in Propeller-Blades, of which the following is a specification.

This invention relates to blades for propellers for air, water or other fluids or for fans or like purposes where adaptable.

One object of my invention is to provide propellers for air-ships, boats, or other devices embodying, among other characteristics, features whereby when it is rotated, the inner portion of the blade forces the air, or other fluids, in any outwardly direction, and the outward portion forces the air, or other fluid, inwardly at any desired angle.

Another object of my invention is to provide propeller blades in which the pitch of the blades at the outer portions is less than that of the inner portion.

Another object of my invention is to provide propeller blades of such construction that they draw air, or other fluid, from a much larger area than the diameter of rotation of the propeller, and compress this air or other fluid between the rotating inner portion of the blade and the outer rotating portion of the blade.

With the above and other objects in view, the invention consists in the construction and novel combination of parts, hereinafter more fully described, illustrated in the accompanying drawings, and pointed out in the appended claims, it being understood that various changes in the form, proportion, number of blades, size and minor details of construction and materials, may be resorted to without departing from the spirit or sacrificing any of the advantages of the invention.

In the drawings:—Figure 1 is a face view of a propeller embodying my improvements. Fig. 2 is a sectional view on the line *a—a* of Fig. 1. Fig. 3 is a sectional view on the line *b—b* of Fig. 1. Fig. 4 is a sectional view on the line *c—c* of Fig. 1. Fig. 5 is a transverse sectional view through the hub of the propeller. Fig. 6 is an end view of the propeller. Fig. 7 is a top plan view.

Referring now more particularly to the accompanying drawings, the propeller embodies a hub 10, from each side of which extend one or more feathering blades 12—12.

each formed alike but disposed in opposite directions, when more than one blade is employed.

The hub formed at the central portion 10 may be integral with the propeller blades, as shown, or may be a separate piece to which the blades are attached, which is especially desirable when three or more are employed. In this hub 10 I have formed the opening 19 of a suitable shape to mount upon the operating shaft 17, and I have provided the threaded screw hole 18 for a set screw (not shown) to secure the hub in operable position on the shaft 17. Extending outwardly from this central hub, are two or more blades adapted, as hereinafter explained, to press against the air or other fluids when rotated.

The forward or outer side of each blade 75 is slightly convexed in a transverse direction throughout the entire length, the object and purpose thereof being to provide thickness for strength at its middle portion, and by gradually reducing the thickness toward the 80 cutting edges to thereby reduce the resistance in rotating in the air or other fluids.

On the rear or inner side, the blades are formed with a suitable pitch to press against the air or other fluids as they are rotated. 85 And to better accomplish this purpose, I have formed each blade with a cutting edge starting from a point almost opposite the middle opening 19 and extending outward in a plane at an angle in front of the plane 90 of the front surface of the hub and extremities of the blades for about two-thirds the length of the blade say for instance, to the point 12' and from this point the blade is rapidly curved rearward, until the 95 tip 16 is in practically the same plane as the rear surface of the hub. The rear or inner surface of each blade is preferably slightly convexed transversely adjacent the hub, as shown in Fig. 2. This convexed portion on the rear or inner surface of each blade adjacent the hub gradually merges into a substantially flat surface, as shown in Fig. 3, from which the inner surface merges into a concaved inner surface at the 105 outer end of the blade, as shown in Fig. 4.

The inner two-thirds of the rear surface extending from the hub 10 to the point 12' is disposed at such an angle to the plane of rotation as to give to the propeller blade 110 such pitch as is desired for the purpose employed. From about the point 12' the pitch

is diminished rapidly leaving about one-half the pitch from the point 12 to the tip 16 as is given to the portion from the hub to the point 12'.

5 It will be seen from the foregoing, that whenever the propeller blade is rotated rapidly in air or other fluid, that the rear inner or pushing surface of the blades push against the air or other fluid as they rotate, 10 thereby creating a forward pressure on the object sustaining said propeller and a rearward motion of the air or other fluid. It will also be seen, that because of the plane at which the inner two-thirds of each rear surface is disposed with relation to the plane of rotation it forces the air or other fluid in which the blades are rotated in an outward direction at an angle to such surfaces. It will also be seen that the outer one-third, by 15 reason of its inward curve, will draw air or other fluid from without the circle of rotation, and will force this air or other fluid inwardly at an angle to said outer ends. The impact of the air or other fluids meeting 20 from the inner and outer portions of the blades, compresses the air and thereby give resistance pressure greater than ordinary atmospheric pressure. It will also be seen, that the forcing of the air outward by the inner 25 portion of the blades tends to produce a vacuum near the center and thereby reduces the air resistance of any body passing through the air immediately to the rear of the middle portion. It will also be seen, that 30 by reducing the pitch of the outer one-third, the amount of power required to rotate it is lessened, and the strain upon the blade is reduced.

It will be seen that whenever the pressure 40 upon the blades causes them to bend near the extremity, they will be lengthened and on account of the curve being so great, will continue to perform the functions as aforesaid, and not merely whip the air or other 45 fluids outwardly, as would occur in case of the bending of ordinary straight blades at their extremities.

What is claimed is:—

1. A propeller comprising a hub and two

or more oppositely disposed blades, each 50 blade having its outer side convexed slightly in a transverse direction throughout its length with its inner face adjacent the hub slightly convexed and with its outer end spoon-shaped and concaved on its inner surface, the inner face of the blade between the concaved and convexed portions being only slightly concaved.

2. A propeller comprising a hub and a plurality of blades each blade being curved 60 gradually outward and at its end directed inwardly with one face slightly convexed in a transverse direction throughout its length and with its opposite face concaved with the greater concavity formed at the outer 65 end of the blade so that upon rotation of the blades the fluid is forced inwardly from the outer ends of the blades and compressed between the inner and outer ends of the 70 blades.

3. A propeller comprising a hub and a plurality of blades, each blade having one side convexed throughout its length and terminating in a curved extremity, and with its opposite side convexed adjacent the hub 75 and being concaved gradually from its convexed portion to its outer extremity, with that portion adjacent its convexed portion disposed upon an inclined plane to the plane of rotation of the propeller with the 80 inclined portion of one plane disposed opposite to the inclined plane portion of the other blade.

4. A propeller comprising a hub and blades extending from the hub, each blade 85 being convexed on one side and curved at its extremity, the opposite side of the blade adjacent the hub being convexed and gradually concaved from its convexed portion to the outer end of the blade with the greater 90 concavity of the blade formed adjacent the base of the curved extremity of the blade.

In testimony whereof I affix my signature in presence of two witnesses.

LEON TROXLER.
